SEALING MEANS FOR ELECTRIC SWITCH GROUND BOXES

Samuel Thomas Quilliam, Manchester, England, assignor to Cheetham Electric Switching Device Co., Incorporated, Louisville, Ky., a corporation of Kentucky

**Application February 13, 1933, Serial No. 656,573
In Great Britain March 2, 1932**

3 Claims. (Cl. 286—9)

The invention relates to improved means for application to boxes for electrical mechanism or like appliances wherewith mercury sealing means of circular or endless forms are provided.

Such-like sealing means are, for example, made use of in boxes or containers of mechanism employed for electrically operating tramway or railway points, and electrical switches, to which mechanism my present invention is particularly applicable.

With regard to boxes of this type, an example of which is illustrated, in part, in the specification of my British Patent No. 305,447, filed March 2, 1932, it is very essential to keep said mechanism free from moisture, for which purpose operating shafts of the apparatus are formed with circular depending lips or flanges, which dip into a mercury seal in the lid or cover, the reservoir or container of said mercury being also circular in form, to suit.

20 In term, to said.
When a lid or cover of this type of apparatus
with its operating shaft and depending flange
thereof is removed for inspection, repairs or
cleaning operations, the mercury in the reservoir
25 named is liable to be spilled, and unless the
amount so lost is replaced to a sufficient extent,
water or moisture may subsequently enter the
box below the lid or cover concerned, eventually
resulting in damage to the parts within, such as
30 the ultimate burning out of the solenoidal coils or
motors or electrical apparatus with which said
boxes are provided.

The object of my invention is to provide an improved form of reservoir of the kind herein named, from which the mercury cannot escape on the tilting or displacement of the lid or cover referred to, taking place.

For this purpose, I provide for the lid or cover a reservoir for mercury which consists of a circumferentially formed cavity adapted for containing mercury of the required quantity at a lower portion thereof, but provided at an upper part with a continuous outer wall and a discontinuous inner wall, or maybe walls, in a depending position, the discontinuity of the inner wall leaving a communication between said upper and lower portions of the cavity. The cavity or chamber is so formed or adapted as to permit of the depending flange of the operating shaft concerned, in the case of a box or container named herein, dipping into the contained mercury to the necessary extent to form a water or moisture proof seal, when said shaft is in position.

The circular form of the reservoir in the lid or cover enables the said reservoir to be situated

about the shaft referred to, which shaft is employed for transmitting motion from internal solenoid coils, or a motor or electrical apparatus, to the point or like mechanism operated by said appliance.

But the invention is applicable to electrical switches of the kind provided with shafts or handles which are, or may be formed with depending lips of circular character, parallel to a horizontal plane, or thereabouts.

In the accompanying drawing, Fig. 1 is a sectional elevation along the end of a box of the type according to my patent herein named, and provided with means arranged in accordance with one form of my present invention.

Fig. 2 is a modification of Fig. 1, and in both figures only so much of the interior of a box is shown to make the application of my said invention thereto sufficiently clear.

The outer casing of the box is shown at 1, a revolute shaft for the same, and operated by the solenoidal or other mechanism (not shown) being indicated at 2.

The outer part of said shaft is marked 3, while an inner cover for the solenoidal parts is indicated at 4. 25

The shaft 2 is formed as usual with a circular depending lip 5, and external of said shaft, which lip or flange dips into a mercury seal indicated at 1. A larger lip 6 is shown provided for the cover 4.

According to my invention, the reservoir containing the mercury at 7, at its lower part, is of circumferential form here for passing around the position of the shaft 2, and above the level of the mercury 7 aforesaid the cover is provided with a cavity part having a continuous outer wall such as at 8, and a discontinuous inner wall of a depending character, such as 9 in Fig. 1.

In Fig. 2, a pair of discontinuous depending walls are employed passing around the reservoir. In the last-named example a further wall is provided adjacent to the shaft 2, but in the case of Fig. 1 the usual bearing for said shaft forms a continuous wall for completing the reservoir. 40

It will be observed that, in the examples given, there is a sloping surface leading from the trough containing mercury to the outer wall, or walls, 8, and it will be obvious on account of the principle made use of in the manner shown, that should the cover 4, for example, with the shaft in position, be removed, and the said cover 4 be tilted, the mercury will flow into the cavity marked 10, according to the direction of tilting, and will be prevented from escape by the inner wall 9. 45

I prefer that the sectional area of the cavity 10 shall be sufficient to accommodate the area of mercury in the same plane when the cover, such as 4, with the shaft 2 in position, is tilted in the 5 said plane through an angle of 90 degrees from the vertical.

In the present example, the reservoir described is formed as part of the cover 4, in Fig. 1, but this is not at all essential.

10 Although Fig. 2 here relates more particularly to Fig. 1, or to a type of electrical street box, it is clear that the device shown in said Fig. 2 could be applicable to a switch, part 3 being a portion or continuation of the shaft or handle of 15 said switch.

The dimensions and shapes of the parts employed for the improved reservoir would obviously be capable of alteration to suit different 20 mechanisms or appliances, without altering the principle involved.

Having now particularly described and ascertained the nature of my said invention and in what manner the same is to be performed, I declare that what I claim is:

1. Sealing means for a rotatable shaft extending through a cover of a fluid tight housing, comprising a cup-shaped member fixed to the shaft and projecting into a liquid disposed in a well 30 in said cover, an inverted trough having inner and outer annular walls surrounding said cup-shaped member, said outer wall being fixed to said cover, said inner wall providing an aperture having a diameter greater than the outside 35 diameter of said cup-shaped member and con-

structed and arranged to retain said liquid irrespective of the position of the cover.

2. Sealing means for a rotatable shaft extending through a lid of a fluid tight housing, comprising a cup-shaped member fixed to the shaft 5 and projecting into a liquid normally disposed in a well fashioned in said lid, an inverted trough surrounding said cup-shaped member and serving as a reservoir for said liquid whenever the lid is moved from a normal position, said trough 10 having an outer wall fixed to said lid and an inner wall encircling said cup-shaped member, said inner wall providing an aperture having a diameter greater than the outside diameter of said 15 cup-shaped member so as to permit removal of said cup-shaped member while said trough is fixed to said lid.

3. Sealing means for a rotatable shaft extending through a horizontal cover of a fluid tight housing, comprising an inverted cup-shaped member 20 fixed to the shaft and projecting into a liquid normally disposed in a well in said cover, an inverted trough encircling said cup shaped member and serving as a reservoir to prevent escape of said liquid whenever said cover is moved 25 from the horizontal position, said trough having an outer wall fixed to said cover and an inner wall loosely disposed about said cup-shaped member, said inner wall providing an opening larger than the outside diameter of said cup-shaped 30 member so as to permit removal of said cup-shaped member and shaft while said trough is fixed to said lid, and thereby prevent escape of said liquid while in said disassembled condition.

SAMUEL THOMAS QUILLIAM. 35
